(57) **CLAIM**

The ornamental design for a fishing lure, as shown and described.

DESCRIPTION

FIG. 1 is a top perspective view of the fishing lure of the present invention;

FIG. 2 is a bottom perspective view of the fishing lure of the present invention;

FIG. 3 is a top plan view of the fishing lure of the present invention;

FIG. 4 is a bottom plan view of the fishing lure of the present invention;

FIG. 5 is a right side elevation view of the fishing lure of the present invention;

FIG. 6 is a left side elevation view of the fishing lure of the present invention;

FIG. 7 is a front elevation view of the fishing lure of the present invention; and,

(Continued)

FIG. 8 is a rear elevation view of the fishing lure of the present invention.

1 Claim, 4 Drawing Sheets
